Assistant Examiner — Jessica Lynn Devilbiss

(57) **CLAIM**

The ornamental design for a vehicle, toy replica, and/or other replica, as shown and described.

DESCRIPTION

FIG. 1 is a front and left perspective view of a vehicle, toy replica, and/or other replica showing our new design;

FIG. 2 is a rear and left perspective view of the vehicle, toy replica, and/or other replica of FIG. 1;

FIG. 3 is a front elevation view thereof;

FIG. 4 is a left side elevation view thereof;

FIG. 5 is a right side elevation view thereof;

FIG. 6 is a rear elevation view thereof; and,

FIG. 7 is a top plan view thereof.

The broken lines in the drawings depict portions of the vehicle, toy replica, and/or other replica that form no part of the claimed design.

1 Claim, 7 Drawing Sheets
